UNITED STATES PATENT OFFICE

157,279

METER CASE FOR SELF-SERVICE GASOLINE PUMPS

Edward J. O'Toole, Burbank, Calif.

Application March 24, 1949, Serial No. 1,585

Term of patent 3½ years

(Cl. D52—2)

To all whom it may concern:

Be it known that I, Edward J. O'Toole, a citizen of the United States, residing at Los Angeles, in the county of Los Angeles and State of California, have invented a new, original, and ornamental Design for a Meter Case for Self Service Gasoline Pumps, of which the following is a specification, reference being had to the accompanying drawing, forming part thereof.

Fig. 1 is a perspective view of a meter case for self service gasoline pumps showing my new design.

Fig. 2 is a plan view, and
Fig. 3 is a full front elevation.

I claim:

The ornamental design for a meter case for self-service gasoline pumps, as shown.

EDWARD J. O'TOOLE.
